Primary Examiner — Catherine R Oliver-Garcia

(57) **CLAIM**

The ornamental design for a light-up fishing pole kit, as shown and described.

DESCRIPTION

FIG. 1 is a top view of the light-up fishing pole kit showing my new design, it being understood that the phantom lines are for illustrative purposes only and form no part of the claimed design;

FIG. 2 is a left view of the light-up fishing pole kit of FIG. 1, it being understood that the phantom lines are for illustrative purposes only and form no part of the claimed design; FIG. 3 is a partial left view of the upper end of the light-up fishing pole kit of FIG. 1, it being understood that the phantom lines are for illustrative purposes only and form no part of the claimed design;

FIG. 4 is a partial left view of the middle of the light-up fishing pole kit of FIG. 1, it being understood that the phantom lines are for illustrative purposes only and form no part of the claimed design; and,

FIG. 5 is a partial left view of the lower end of the light-up fishing pole kit of FIG. 1, it being understood that the phantom lines are for illustrative purposes only and form no part of the claimed design.

1 Claim, 5 Drawing Sheets
